PENTANE DEHYDROGENATION

John B. Maerker, Secane, Pa., assignor to Houdry Process Corporation, Wilmington, Del., a corporation of Delaware

Filed July 16, 1958, Ser. No. 749,014

5 Claims. (Cl. 260—680)

This invention relates to the dehydrogenation of pentane.

The usefulness of a gasoline in starting an internal combustion motor in cold weather is dependent in part upon the more volatile components. A full range gasoline must include appropriate components to impart a controlled volatility to the gasoline. Some volatile compounds, such as propane, isobutane, and isobutene possess high octane numbers and accordingly, possess advantages over normal pentane as volatile components for the gasoline.

Normal pentane has an F-1 octane number of 61.7 and a blending value which may be as low as 57. The miscellaneous markets for normal pentane as a solvent, as a raw material for chemical manufacture and the like have been extremely small relative to the quantities of technical pentane produced in the normal operation of petroleum refineries and natural gasoline plants. Accordingly, normal pentane has been much used in gasoline, notwithstanding its low octane number. Inasmuch as normal pentane tends to depress the octane number of the gasoline pool significantly more than other volatile components would, the use of normal pentane in gasoline has to a certain extent increased the need for capacity to produce high octane number components, such as ethylbenzene, xylene and the like for achieving any particular octane number in the gasoline pool.

As the market demand for higher octane gasoline has required raising of the octane number of the gasoline pool, the disadvantages of using normal pentane in the gasoline have increased significantly. Although normal pentane is not particularly disadvantageous and/or costly to use (i.e. necessitating increased facilities to prepare sufficient high octane components to counteract the effect of low octane number pentane) in a gasoline having an octane number of 80, even minor amounts of normal pentane are undesirable in premium gasoline having an F-1 octane number above 100. Normal pentane has previously generally been disposed of as a component of gasoline thus operating more profitably than by disposing of the normal pentane as an inexpensive fuel, but the reverse might prevail if there were a sufficient demand for gasoline having an octane number above 100.

Heretofore, it has been recognized that the 92.3 octane number of pure isopentane and especially the 89 blending value of isopentane were more attractive than the 61.7 and 57 values for normal pentane. It has also been known that 2 methyl 2 butene has an octane number of 99.1 and that the octane numbers of the several other isopentenes and even the several normal pentenes were significantly higher than 61.7.

It has long been recognized that a plant could be designed to convert normal pentane into isopentene. However, petroleum technologists have recognized that there were more profitable refinery improvements, even if one were to assume that the isopentene could be marketed at a price equal to that of other high octane gasoline, and even if one were to assume that the normal pentane feed had a value as low as the value of residual fuel oil, inas-

2

much as the operating cost and required investment of such a plant would be so high. Certain of the necessary separation steps in such a hypothetical plant are both difficult and costly. The 8° C. difference between the boiling points of normal pentane and isopentane is so small that the preparation of a grade of isopentane containing less than about 5% normal pentane is relatively costly. The separation of saturated from unsaturated hydrocarbons is more difficult and costly when dealing with C₅ hydrocarbons than when dealing with C₃ or C₄ hydrocarbons. The existence of numerous isomers makes the olefin-diolefin separation very much more difficult for C₅ hydrocarbons than for C₄ hydrocarbons. In the manufacture of C₄ diolefins, the concentration of isomers other than the desired 1,3 butadiene is so small that it can be ignored. However, in the manufacture of isoprene, significant amounts of piperylene and/or other C₅ diolefins tend to be produced, and must be separated in order to market a commercially attractive grade of isoprene. Although small quantities of isoprene have been manufactured as by-products of certain thermal processing of hydrocarbons, no commercial plant for the manufacture of isoprene from C₅ hydrocarbons has been constructed, notwithstanding the available market for isoprene at a price significantly higher than the price at which butadiene is sold.

Prior workers concerned with isomerization reactions have noted that the reaction rate at which skeletal isomerization occurs in C₅ hydrocarbons is significantly higher for unsaturated hydrocarbons than for saturated hydrocarbons. The prior art connoted that the best procedure for converting normal pentane to isopentene required first dehydrogenating to form normal pentenes and then catalytically isomerizing to form isopentenes.

35 Various thermodynamic and reaction rate studies have enhanced the attractiveness of this chronology of the process steps (dehydrogenation and then isomerization) for converting normal pentane to isopentenes.

40 Various procedures have been proposed for converting normal pentane to isopentane, and for separating the isopentane from the product. Such methods have generally involved the use of a recycle ratio which was so high and/or such excessive cost for the separation of the isopentane from the effluent from the isomerization zone that such proposals have not been widely adopted. In recent years, it has been established that by the use of superatmospheric pressure, several mols of hydrogen per mol of hydrocarbon, and a catalyst consisting predominantly of alumina and containing minor amounts of halide 45 and minor amounts of platinum, the hydroisomerization of normal pentane to isopentane could be conducted for long periods of operation without regeneration. There has not been a wide spread adoption of such a method because refinery managers have deemed other possible 50 improvements to be more profitable.

55 In accordance with the present invention, a gasoline component having a high octane number because of its isopentene content is prepared from a pentane charge stock containing a major proportion of the normal isomer by a multi-step method in which the investment costs and operating costs are kept remarkably low by the correct relationship among the process steps. This method involves the steps of: mixing a feedstock stream consisting predominantly of normal pentane with a recycle stream consisting predominantly of C₅ acyclic hydrocarbons; passing said mixture, together with several mols of hydrogen per mol of hydrocarbons, over a platinum on halided alumina catalyst at isomerization conditions including a space rate from 1 to 6 volumes of liquid hydrocarbon per volume of catalyst per hour, a pressure of from 15 to 50 atmospheres, and a temperature of

600° to 950° F.; subjecting the hydrocarbon effluent from the isomerization catalyst to dehydrogenation over a chromia on alumina catalyst at a liquid space rate of from 0.5 to 3, a pressure from 0.1 to 2 atmospheres, and a temperature from 900° F. to 1200° F.; separating from the effluent from the dehydrogenation catalyst unconverted paraffins for inclusion in said recycle stream; subjecting a diolefin-containing fraction in the liquid phase to selective hydrogenation over a catalyst comprising copper chromite at a temperature from 60° F. to 320° F. at a liquid space rate from 0.5 to 6 per hour, at a hydrogen to hydrocarbon ratio of from 0.01 to 1 to prepare an olefin stream substantially free from diolefins; and withdrawing a stream of pentenes containing

5 pressure of 230 pounds per square inch at a temperature of 825° F. and a space rate of 4 volumes of liquid pentane per volume of catalyst per hour to form an isomerate consisting of about 61% isopentane and 39% normal pentane.

EXAMPLE II

Liquid C₅ hydrocarbons were separated from the hydrogenative isomerization step of Example I and found to consist essentially of 61% isopentane and 39% normal pentane. Such a mixture was subjected to dehydrogenation at atmospheric pressure over a catalyst consisting of chromia on alumina, varying process conditions as indicated in Table I.

a high proportion of isopentenes as a fraction for imparting both a high octane number and controlled volatility to a fuel for high compression internal combustion motors.

In various modifications and/or subcombinations of modifications of the invention: the hydrocarbons subjected to the chromia on alumina catalyst are admixed with from 0.1 to 6 mols of hydrogen; the hydrogen to hydrocarbon ratio in the dehydrogenation step is substantially the same as the ratio in the isomerization step; the unsaturated hydrocarbons remaining after the separation of the paraffinic recycle stream are separated to form a monoolefin rich stream and a diolefin-rich stream, the diolefin rich stream is separated to recover an isoprene stream, withdrawing said isoprene stream as a product of the process, subjecting only the non-isoprene fraction of the diolefin rich stream to the selective hydrogenation step, and mixing the effluent from said selective hydrogenation step with the monoolefin-rich stream to form said stream of pentenes; the dehydrogenation is conducted at a total pressure of from 0.1 to 0.5 atmosphere and in the presence of from 0.1 to 1 mol of hydrogen per mol of hydrocarbon at a temperature between 1000° F. and 1200° F. to produce a substantial yield of isoprene with minimized coke formation; or the dehydrogenation is conducted at a total pressure of from 1 to 2 atmospheres and in the presence of from 0.5 to 3 mols of hydrogen per mol of hydrocarbon at a temperature between 1000° F. and 1200° F. to produce a substantial yield of pentenes with minimized diolefin formation and with minimized coke formation.

The accompanying flow sheet indicates the relationship of several processing steps and the flexibility of the invention by reason of the optional character of certain steps. Thus, the present invention provides for a plant which can be operated with flexibility and which can adapt to the changing market prices and demands for various starting materials and/or products.

EXAMPLE I

Technical grade n-pentane, mixed with 2 mols of hydrogen per mol of pentane is subjected to an isomerization zone containing a catalyst consisting of 96.5% gamma alumina, 3% chloride, and 0.5% platinum at a

35 pressure of 230 pounds per square inch at a temperature of 825° F. and a space rate of 4 volumes of liquid pentane per volume of catalyst per hour to form an isomerate consisting of about 61% isopentane and 39% normal pentane.

at room temperature and 5 atmospheres' pressure to prepare a purified pentene stream. To the extent that the pentene raffinate contains trace amounts of diolefins, these gum-formers are removed by the selective hydrogenation. The thus purified pentene stream is withdrawn as a product useful for imparting both a high octane number and controlled volatility to gasoline.

The ability of the method to prepare not merely attractive yields of technical isoprene but still larger amounts of high octane motor fuel of the high volatility (crude isopentenes, normal pentenes mixture) justifies the capital investment in the catalytic and separation apparatus. The flexibility in operation permits adaptation to the peculiarities of the marketing conditions. If there were a great demand for pentenes for gasoline, but almost no market for isoprene, the dehydrogenation step would be conducted at about atmospheric pressure, and the diolefin separation step would be omitted, and the entire unsaturated fraction would be subjected to the selective hydrogenation to eliminate troublesome quantities of diolefins, and to make feasible the preparation of large quantities of pentenes having good anti-knock characteristics. Surprisingly, the separation of a paraffinic recycle stock from the dehydrogenation zone is more advantageous in upgrading octane number per unit investment cost than the separation of a normal pentane recycle stock for the isomerization step and the separation of a moderately pure isopentane recycle stream for the dehydrogenation step. The normal pentenes have octane numbers significantly less than those of the isopentenes. However, because the isomerate contains so much isopentane, and because the dehydrogenation is measurably selective for the isopentane, the concentration of the normal pentenes in the predominantly isopentene product from the dehydrogenation zone is not so excessive as to lower the octane number below the limits tolerable in high octane gasoline.

EXAMPLE IV

Pentane is subjected to hydrogenative isomerization using the catalyst, pressure and temperature of Example I, but using approximately double the space rate, whereby the product contains about 38% isopentane and 62% normal pentane. Certain natural gasoline fractions have about this same isomer distribution. Such pentane mixture is dehydrogenated at atmospheric pressure and in the presence of 1 mol of H_2 per mol of pentane over a chromia on alumina catalyst, starting at 975° F. and raising the temperature to 1025° F. during a 12 hour run. The C_5 fraction is separated from the effluent, and extractively distilled to provide a paraffinic recycle stream and an unsaturated product. Selective hydrogenation of the diolefin content of the pentene fraction in the liquid phase over a copper chromite catalyst provides a fraction useful for imparting both a high octane number and volatility to gasoline.

EXAMPLE V

A mixture of 62% normal pentane and 38% isopentane was dehydrogenated over a chromia-alumina catalyst at 1000° F. and 1 atmosphere pressure. The space rate and hydrogen to hydrocarbon ratio were adjusted in five runs as shown in Table II.

Table II

HYDROGENATIVE DEHYDROGENATION

Run No.	10	11	12	13	14
V/V./Hr.	2	1	1	1	1
°F.	1,000	1,000	1,000	1,000	1,000
H_2/HC ratio	0.0	0.5	1	2	4
Yield:					
C_5 wt. percent	93.1	94.8	98	96.3	93.2
C_5H_{10}	22	27	22	26	27
carbon	2.0	1.1	0.4	0.2	0.1
Dehydro sel.	80	88	93	90	85
F-1 clear	90	95	89	88	88

These data establish that at the conditions tested, any hydrogen to hydrocarbon ratio within the range from about 0.3 to about 5 possessed advantages meriting engineering evaluation, and that surprisingly superior results are attainable within the range from about 0.3 to about 1.5 H_2/HC ratio.

EXAMPLE VI

The effect of long on-stream dehydrogenation was tested at atmospheric pressure, 1025° F. and allowing the total reaction mixture to be in contact with the catalyst for a constant time period, as shown in Table III.

15

Table III
LONG CYCLE DEHYDROGENATION

Run No.	15			16			17		
V/V./Hr.	2			1			0.5		
°F.	1,025			1,025			1,025

F-1 clear	89	86.5	83.6	94.1	90.8	87.5	87	86.2	

This and similar data helped to establish that the presence of hydrogen in the reaction mixture enhanced the stability of the performance of the process sufficiently to make a long cycle dehydrogenation method feasible.

35

In determining whether a dehydrogenation unit should be operated at an increasing temperature or at a constant temperature, comparative runs were made. In one, the temperature was constant at 1025° F., and in the other, the temperature was 975° for the first two hours, 1000° for the next six hours and 1025° for the last four hours of twelve hour tests, as shown in Table IV.

45

Table IV
CONSTANT VERSUS INCREASING TEMPERATURE

Run No.	18 Constant				19 Increasing T			
Type								
V/V./Hr.					1			
H_2/HC					1			
Hours	2	4	8	12	2	4	8	12
Conversion	40	32.5	24.8	20.5	30.5	25	27.5

Dehydro sel.	82	81	83	82	86	93	92	
F-1 clear	92	94.2	87.5	91.5	84.7	86.8	89	86.5

55

By such and similar data, it was established that the temperature is advantageously increased during each dehydrogenation cycle, thereby at least partially overcoming the temporary decrease in catalyst activity prior to each regeneration.

EXAMPLE VIII

When mixtures of normal pentane and isopentane are dehydrogenated, the selectivity for isopentane dehydrogenation is significant, but some normal pentene is also formed as a result of the competitive reactions. It is difficult and expensive to analyze the mixture of normal pentenes and isopentenes. Reasonable estimates of the isopentene selectivity can be obtained on the basis of the dehydrogenation of the separate pentane isomers at identical conditions. Dehydrogenation tests were conducted on the compounds as shown in Table V, in which "I" designates isopentane and "n" designates normal pentane.

7
Table V
COMPARISON OF DEHYDROGENATION OF NORMAL AND
ISOPENTANE

Run No. Type	20 i	21 n	i/n	22 i	23 n	i/n

Dehydro sel.	94.2	91.7	1.03	89.1	77.7	1.15

Obviously many modifications and variations of the invention as hereinbefore set forth may be made without departing from the spirit and scope thereof, and therefore only such limitations should be imposed as are indicated in the appended claims.

The invention claimed is:

1. The method of preparing both isoprene and a C₅ fraction of high octane number from a feedstock stream consisting predominantly of normal pentane which includes the steps of: mixing a feedstock stream consisting predominantly of normal pentane with a recycle stream consisting predominantly of C₅ acyclic saturated hydrocarbons; passing said mixture, together with several mols of hydrogen per mol of hydrocarbon, over a platinum on halided alumina catalyst at isomerization conditions including a space rate from 1 to 6 volumes of liquid hydrocarbon per volume of catalyst per hour, a pressure of from 15 to 50 atmospheres and a temperature of 600° to 950° F.; subjecting all of the C₅ hydrocarbon effluent from the isomerization catalyst to dehydrogenation over a chromia on alumina catalyst at a liquid space rate of from 0.5 to 3 volumes of liquid C₅ hydrocarbon per volume of catalyst per hour, a pressure from 0.1 to 2 atmospheres, and a temperature from 900° F. to 1200° F.; separating from the effluent from the chromia on alumina dehydrogenation catalyst unconverted C₅ acyclic saturated hydrocarbons for inclusion in said recycle stream; separating from the effluent from the dehydrogenation catalyst a stream consisting essentially of pentenes, isoprene and, miscellaneous pentadienes; separating and withdrawing isoprene from the effluent from the dehydrogenation catalyst; subjecting the raffinate remaining after isoprene withdrawal to selective hydrogenation over a catalyst containing copper chromite at a temperature from 60° F. to 320° F. at a liquid space rate from 0.5 to 6 volumes of liquid raffinate per volume of catalyst per hour at a hydrogen to hydrocarbon ratio of from 0.01 to 1 to selectively hydrogenate the miscellaneous pentadienes to pentenes and to prepare a pentene stream substantially free from diolefins; and withdrawing said stream of pentenes containing a high proportion of isopentenes as a fraction for imparting both a high octane number and controlled volatility to a fuel for high compression internal combustion motors.

2. The method according to claim 1 in which the hy-

drocarbons subjected to the chromia on alumina catalyst are admixed with from 0.1 to 6 mols of hydrogen.

3. The method according to claim 1 in which the hydrogen to hydrocarbon ratio in the dehydrogenation step is substantially the same as the ratio in the isomerization step.

4. The method according to claim 1 in which the dehydrogenation is conducted at a total pressure of from 0.1 to 0.5 atmosphere and in the presence of from 0.1 to 1 mol of hydrogen per mol of hydrocarbon at a temperature between 1000° F. and 1075° F. to produce a substantial yield of isoprene with minimized coke formation.

5. A method of preparing a fraction rich in isopentenes from a feed stock stream consisting predominantly of acyclic C₅ hydrocarbons which includes the steps of: mixing a feed stock stream consisting predominantly of acyclic C₅ hydrocarbons with a recycle stream consisting predominantly of C₅ acyclic hydrocarbons; passing said mixture together with several mols of hydrogen per mol of hydrocarbon over a platinum on halided alumina catalyst at isomerization conditions including a space rate of from 1 to 6 volumes of liquid hydrocarbon per volume of catalyst per hour, a pressure of from 15 to 50 atmospheres and a temperature of from 600° F. to 950° F.; subjecting all of the hydrocarbon effluent from the isomerization catalyst directly to dehydrogenation over a chromia on alumina catalyst at a liquid space rate of from 0.5 to 3, a pressure of from 0.1 to 2 atmospheres, and a temperature of from 900° F. to 1200° F., whereby some of the normal pentane is dehydrogenated to normal pentenes and more of the iso-pentane is dehydrogenated to iso-pentenes; separating from the effluent from the dehydrogenation catalyst unconverted paraffins for inclusion in said recycle stream; separation from the effluent from the dehydrogenation catalyst a stream consisting predominantly of pentenes and pentadienes; subjecting a fraction comprising a major amount of pentenes and a minor amount of pentadienes to selective hydrogenation over a catalyst containing copper chromite at a temperature of from 60° F. to 320° F. at a liquid space rate of from 0.5 to 6 per hour at a hydrogen to hydrocarbon ratio of from 0.01 to 1 to selectively hydrogenate the pentadienes to pentenes and to prepare a pentene stream containing not more than trace amounts of diolefins; and withdrawing a stream of pentenes containing a high proportion of iso-pentenes as a fraction for imparting both a high octane number and controlled volatility to a fuel for high compression internal combustion motors.
